UNITED STATES PATENT OFFICE.

MARTIN MARTINSON, OF KENOSHA, WISCONSIN, ASSIGNOR OF ONE-HALF TO BERT L. SHAW, OF KENOSHA, WISCONSIN.

PIN-SETTING APPARATUS FOR BOWLING-ALLEYS.

1,111,481.

Specification of Letters Patent. Patented Sept. 22, 1914.

Application filed November 14, 1913. Serial No. 800,960.

To all whom it may concern:

Be it known that I, MARTIN MARTINSON, a citizen of the United States, and a resident of the city of Kenosha, county of Kenosha, 5 and State of Wisconsin, have invented certain new and useful Improvements in Pin-Setting Apparatus for Bowling-Alleys, of which the following is a specification.

My invention relates to improvements in 10 pin-setting apparatus for bowling-alleys and has for its object the production of apparatus of this character which will be durable and economical in construction and through the medium of which pins may be set and 15 spotted upon a bowling-alley with ease and expedition.

Other objects will appear hereinafter.

The invention consists in the combinations and arrangements of parts hereinafter described and claimed.

The invention will be best understood by reference to the accompanying drawings forming a part of this specification, and in which—

25 Figure 1 is a top plan view of the rearward end of a conventional bowling-alley equipped with pin-setting apparatus embodying my invention, Figs. 2, 3, 4 and 5 are enlarged detail sections taken on substantially lines $u-u$, $v-v$, $w-w$ and $x-x$ respectively of Fig. 1, Figs. 6 and 7 are similar sections taken on substantially line $y-y$ of Fig. 1, showing the carrier of the pin setter in the different positions which the same 30 assumes in the operation thereof, and Fig. 8 is an enlarged detail section taken on line $z-z$ of Fig. 3.

The preferred form of construction as 35 illustrated in the drawings comprises a carrier substantially triangular in outline upon which the pins are adapted to be arranged in the pin-setting operation. This carrier comprises a substantially V-shaped peripheral portion or frame 1 formed preferably 40 of angle iron at the rearward ends of which are fastened metallic angular members 2. Extending between and securely fastened at their ends to the members 1 and 2 are spaced transversely extending members 3 formed preferably of wood. Secured upon 45 the upper sides of the members 3 and extend-

ing at right angles thereto are elongated members 4 also formed preferably of wood which result in the formation of pin sockets or openings 5. In the pin-setting operation, 55 the pins are arranged in substantially horizontally disposed positions upon the upper sides of the members 3 with their lower or base ends projecting into the sockets 5, as clearly shown in Fig. 6, metallic rubbing 60 plates 6 being preferably provided at the upper sides of said members 3 at the points where the points contact therewith to prevent wear. Arranged at the front side of the sockets 5 are guide members 7, segmental in 65 cross-section adapted, in the pin-setting operation to guide pins to position upon the alley after the same have been rocked to vertical position in the manner hereinafter described.

70 Arranged at the upper side of the carrier is a frame consisting of spaced transversely extending bars 8 and longitudinally extending bars 9, said members 8 and 9 being connected by connecting pieces 10 in which are threaded set screws 11. The foremost bar 8 is formed integral with the forward ends of members 9 and hence the members 10 are dispensed with at these points. The transversely extending bars 8 of said frame are 75 so spaced that, when said frame is in its lowered position said bars will be positioned just rearwardly of the pin sockets 5 and so that the upper ends or heads of pins placed upon the carrier will be positioned directly 80 over said bars as clearly shown in Fig. 6. Said frame is movably connected with the carrier by means of rocker arms 12 and 12', the lower ends of arms 12' being pivotally connected at 13 with said carrier as clearly 85 shown in Fig. 2. The lower ends of arms 12 are fixed to a shaft 14 the respective ends of which are rockingly mounted in bearing 14' provided at the under side of the carrier as clearly shown in Fig. 4. Coöoperating with 90 the arms 12 is a helical torsional spring 15 one end of which is fixed to one of said arms, the opposite end of said spring being fixed to a member 16 which is mounted upon the shaft 14 for rotatable adjustment in order 95 to regulate the tension of said spring. A pin 17 adapted for engagement at its inner 100

end with any one of a plurality of spaced perforations or sockets 17' provided in the periphery of the member 16 and adapted for engagement at its outer end against an adjacent stationary portion of the carrier affords means whereby the tension of said spring may be adjusted, it being clear that, upon weakening, said member 16 may be rotated to compensate for the weakened condition thereof and the pin 17 engaged with the proper socket 17' in order to hold the member 16 against reverse rotation and the spring in its adjusted position. Said frame is so mounted, as will be observed, that when released from its lowered position, the same will move forwardly and upwardly or in such a direction as to effect rocking of the pins, whose upper ends are resting in engagement therewith, upwardly to vertical position so as to pass through the sockets 5. Said frame is releasably held at its lower terminal of movement by means of a detent 18 which is pivoted intermediate its ends at 19 to a stationary supporting piece 20 secured to the under side of carrier members 4, as clearly shown in Fig. 8, the upper end of said detent being adapted to engage over the adjacent bar 8 of the frame as clearly shown in Fig. 3. The lower end of said detent is so positioned that, upon downward rocking of the carrier in the manner hereinafter described, said end of said detent will contact with the upper surface of the bowling-alley and thus be tripped to release the pin rocking frame. Said lower end of said detent is preferably provided with a rubber roller as shown in order to prevent marring of the upper surface of the alley engaged thereby.

The rearward end of the carrier and more precisely the members 2 thereof are rigidly secured to the forward ends of arms 21 which are fulcrumed at their rearward ends as at 22 to the kick boards 23 of the bowling-alley 24. The arrangement is such, as will be observed, that the carrier is positioned directly over the rearward end of the alley and is adapted for pivotal movement toward and from the same. Coöoperating with the arms 21 are levers 26 pivotally secured at 25 intermediate their ends to the kick boards 23, the rearward ends of said levers being connected by means of links 27 with the arms 21 as shown in the several views. Provided at the forward ends of the levers 26 are weights 28 adjustably mounted thereon and secured in positions of adjustment by means of set screws 29. The arms 21 are offset as shown so as to provide clearance for the levers 26 and the forward ends of said levers are offset to provide clearance for the weights 28 carried thereby. The arrangement is such that the levers 26 together with the weights arranged thereon will be adapted to exert such a leverage upon the arms 21 as to be adapted to

normally hold the carrier in elevated position as shown in Fig. 6. In using the device, upon the tenth pin being placed in position upon the carrier, the influence of said levers and weights will be overcome or over-balanced so that, upon replacing of the last pin in position, the latter will automatically swing downwardly to its lower position as shown in Fig. 7.

In the operation of the pin setter then, it will be seen that the carrier will normally assume an elevated position over the alley. In order to set the pins, all that is required of the operator is to arrange the same upon the carrier resting upon the plate 6 with their lower or base ends projecting into the sockets 5 as shown in Fig. 6. The carrier will be held in elevated position by the levers 26 and weights carried thereby until the last pin has been placed upon the carrier, when the influence of said levers and weights will be overcome and over-balanced, the carrier swinging automatically to its lowered position. As the carrier reaches its lowered position the detent 18 is tripped which releases the pin rocking frame 8-9, said frame causing the rocking of the pins to vertical position so as to permit of the same passing through the sockets 5. The upper ends of the pins will be clamped between the bars 8 and the guide members 7 directly over the spots of the alley, being released by the operator engaging the rearward bar 8 of said frame and slightly retracting the same. Upon release of the pins from the carrier the latter is automatically swung to elevated position under the influence of the weighted levers 26. The frame 8-9 is then drawn rearwardly and downwardly by the operator to its initial position where the same will be held by the detent which is adapted to automatically engage therewith when at its lowered position. This being done the setter is again in position for the pin-setting operation.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. In a pin-setting apparatus for bowling alleys, the combination of a carrier upon which the pins are adapted to be arranged in substantially horizontally disposed positions, said carrier being mounted for movement toward and from the alley; a pin-rocking element movably connected with said

in substantially horizontally disposed positions, said carrier being mounted for movement toward and from the alley; a frame arranged at the upper side of said carrier and 5 connected thereto for upward and forward movement, said frame comprising transversely extending members upon which the upper ends of the pins are adapted to rest when arranged upon said carrier, upward 10 and forward movement of said frame from its lower terminal of movement effecting rocking of said pins to vertical positions; a detent for releasably holding said frame at its lower terminal of movement, said detent 15 being adapted to be automatically tripped when said carrier is at its lower terminal of movement; resilient means for moving said frame forwardly and upwardly, when released by said detent; and means for guiding 20 the pins to position upon the alley when the same are rocked to vertical positions, substantially as described.

8. In a pin-setting apparatus for bowling alleys, the combination of a carrier upon 25 which the pins are adapted to be arranged in substantially horizontally disposed positions, said carrier being mounted for movement toward and from the alley; a frame movably connected with said carrier upon 30 which the upper ends of said pins are adapted to rest when arranged upon said carrier, movement of said frame from its lower terminal of movement effecting rocking of said pins to vertical positions; a detent for releasably holding said frame at its lower terminal of movement, said detent being adapted to be automatically tripped to release said frame, when said carrier is in its lowered position; means for actuating said frame to 40 rock the pins when released by said detent; and means for guiding said pins to position upon the alley, when the same are rocked to vertical positions, the pins, when rocked to vertical position by said frame, 45 being clamped in this position between said frame and said guiding means, said frame being manually retractable to release said pins, substantially as described.

9. In a pin-setting apparatus for bowling alleys, the combination of a carrier upon 50 which the pins are adapted to be arranged in substantially horizontally disposed positions, said carrier being mounted for movement toward and from the alley; means 55 movably connected with said carrier upon which the upper ends of said pins are adapted to rest when arranged upon said carrier; means for automatically moving said means to effect rocking of said pins to vertical 60 positions; and means for guiding said pins to the alley when the same are rocked to vertical position, the pins when rocked to vertical position by said first mentioned means, being clamped in this position between 65 said means and said guiding means,

said first mentioned means being manually retractable to release said pins, substantially as described.

10. In a pin-setting apparatus for bowling alleys, the combination of a carrier upon 70 which the pins are adapted to be arranged in substantially horizontally disposed positions, said carrier being mounted for movement toward and from the alley; means movably connected with said carrier upon 75 which the upper ends of the pins are adapted to rest when arranged upon said carrier; a helical torsional spring for automatically moving said means to effect rocking of said pins to vertical position; means for guiding 80 said pins to position upon the alley, when the same are rocked to vertical positions; and means for adjusting the tension of said spring, substantially as described.

11. In a pin-setting apparatus for bowling alleys, the combination of a carrier upon 85 which the pins are adapted to be arranged in substantially horizontally disposed positions, said carrier being mounted for movement toward and from the alley; means 90 movably connected with said carrier upon which the upper ends of the pins are adapted to rest when arranged upon said carrier; a helical torsional spring for automatically 95 moving said means to effect rocking of said pins to vertical position; means for guiding said pins to position upon the alley, when the same are rocked to vertical positions; means for adjusting the tension of said spring, said last mentioned means comprising a disk 100 having spaced recesses in its periphery; and a pin releasably engaging at its inner end with said recesses, the outer end thereof being adapted to engage against a stop, substantially as described.

12. In a pin-setting apparatus for bowling alleys, the combination of a carrier for supporting the pins, said carrier having one end pivotally fastened so as to permit of the free end thereof swinging vertically 110 toward and from the alley; an oscillatory lever arranged at one side of said carrier for yieldingly holding the latter normally in elevated position; and means for automatically delivering the pins from the carrier to the alley when the carrier is in lowered position, said lever upon release of said pins, being adapted to automatically swing said carrier to elevated position, substantially as described.

13. In a pin-setting apparatus for bowling alleys, the combination of a carrier for supporting the pins, said carrier having one end pivotally fastened so as to permit of the free end thereof swinging vertically 115 toward and from the alley; an oscillatory lever arranged at one side of said carrier and a weight adjustably mounted on said lever for yieldingly holding said carrier normally in elevated position; and means 120

for automatically delivering the pins from the carrier to the alley, when the carrier is in lowered position, said weighted lever, upon release of said pins, being adapted to automatically swing said carrier to elevated position, substantially as described.

In testimony whereof I have signed my

name to this specification in the presence of two subscribing witnesses.

MARTIN MARTINSON.
